UNITED STATES PATENT OFFICE.

PAUL EDWARD FLEMING, OF HURON, SOUTH DAKOTA.

DESIGN FOR AN EMBLEM.

50,715.

Specification for Design.

Patented May 8, 1917.

Application filed January 3, 1917. Serial No. 140,467. Term of patent 7 years.

To all whom it may concern:

Be it known that I, PAUL EDWARD FLEMING, a citizen of the United States, residing at Huron, county of Beadle, and State of South Dakota, have invented a new, original and ornamental Design for Emblems, of which the following is a specification, reference being had to the accompanying drawing, forming part thereof.

The figure is a side elevation of an emblem, showing my new design.

I claim:

The ornamental design for an emblem, as shown.

PAUL EDWARD FLEMING.
